(57) CLAIM

The ornamental design for a cart corral with a single panel for advertising, as shown and described.

DESCRIPTION

FIG. 1 is a front perspective view of a cart corral with a single panel for advertising according to our new design; FIG. 2 is a rear perspective view of the cart corral of FIG. 1;

FIG. 3 is a right side view of the cart corral of FIG. 1; FIG. 4 is a left side view of the cart corral of FIG. 1; FIG. 5 is a top view of the cart corral of FIG. 4, such that the left side of the cart corral is positioned above the left side of the cart corral;

FIG. 6 is a front view of the cart corral of FIG. 1; and, FIG. 7 is a back view of the cart corral of FIG. 1. The broken line showing is included for the purpose of illustrating environment and forms no part of the claimed design.
